BOTTLE WASHING MACHINERY

Frank P. Perkins, Waukesha, Wis., assignor to
 Michael Yundt Company, Waukesha, Wis., a
 corporation of Wisconsin

Application May 9, 1941, Serial No. 392,676

9 Claims. (Cl. 15—60)

This invention relates to an improvement in bottle-washing machinery of the type wherein the bottles are carried through a soaking tank, an external brushing mechanism, an internal brushing means and suitable rinsers by a motor-driven conveyor having endless chains carrying individual pockets or compartments for the bottles. The external brushing mechanism includes rotary cleaning brushes disposed above the conveyor. The gearing interposed between the conveyor and its driving motor is of such character as to move the conveyor with step-by-step motion, and during the intervals, when it is at rest, vertically movable bottle-lifting spindles are actuated to engage and lift bottles from the pockets or compartments of the conveyor and pass them between and against the rotary brushes. The action is a timed or synchronized one, and if bottles for any reason jam in the instrumentalities making up the external brushing mechanism, serious breakage or damage to the machine and loss of production results. Any such jamming of the bottles results in a buckling of the endless chains of the conveyor, and the present invention proposes to take advantage of this buckling to automatically stop the machine when such conditions obtain.

In carrying out the present invention, a shoe is provided which rides on a run of the endless or flexible chain conveyor, and is so constituted and related to the conveyor that when the latter buckles upon jamming of the machine, the shoe is elevated or shifted. Such elevation or shifting of the shoe is utilized to operate a control device in such manner as to automatically stop the machine.

The control device preferably includes an electric switch which may be advantageously biased to closed position. A switch-operating lever is combined with the switch and is normally inactive, but when swung in one direction is effective to open the switch. A rotary cam is provided and is cooperatively related to the lever so that when rotated it swings the lever in the direction to open the switch. The cam is interconnected with the shoe by means of suitable linkage or motion transmission mechanism, and this in such manner that when the shoe is elevated or shifted by the buckling of the endless flexible or chain conveyor, the cam will be rotated to swing the lever in the direction to open the switch.

The switch may exercise control over the machine in a number of ways. For example, it may be incorporated in an electric circuit including the electromagnetic winding of a contactor incorporated in the motor circuit for the driving motor for the conveyor. In such a control system the arrangement is such that as long as the control switch is closed the winding of the con-

tactor is energized and the motor circuit is closed so that the motor runs. However, upon opening of the control switch the winding of the contactor is deenergized and the motor circuit is automatically opened and the machine stopped.

Another type of control device contemplated by the present invention is one wherein the control switch is incorporated in an electric circuit including a solenoid, with the solenoid combined with a clutch incorporated in the gearing between the driving motor and the endless conveyor in such manner that when the solenoid is energized it functions to engage the clutch, and when deenergized it provides for disengagement of the clutch and consequent stoppage of the machine.

Other objects of the invention are to provide a device of this character which is extremely simple and compact in its construction, reliable and effective in operation, easy and comparatively inexpensive to manufacture and install, and of such nature as not to interfere with or impair in any way the normal functioning of the machine although always ready for action should the undesirable jamming occur.

Other objects and advantages reside in certain novel features of the construction, arrangement, and combination of parts, which will be herein-after more fully described and particularly pointed out in the appended claims, reference being had to the accompanying drawings forming a part of this specification, and in which:

Figure 1 is a fragmentary view in side elevation with parts broken away and shown in section for the sake of illustration, and showing the external brushing mechanism of a bottle-washing machine and the manner in which the automatic stopping device of the present invention is combined therewith;

Figure 2 is a fragmentary view in top plan of the structure shown in Figure 1, with parts of the enclosing casing for the brush-actuating chain and sprocket gearing removed;

Figure 3 is a transverse section taken on line 3—3 of Figure 2 and showing how the shoe and the other elements interconnected therewith are positioned when the machine is functioning normally;

Figure 4 is a view similar to Figure 3 but showing one of the chains buckled and the shoe elevated to open the control switch and stop the machine;

Figure 5 is an elementary diagram illustrating how the motor is combined with the endless conveyor and with the automatic stopping device of the present invention; and

Figure 6 is a view similar to Figure 5 but showing a different way in which the automatic stopping device may exercise its control over the conveyor drive.

Referring to the drawings, the numeral 10 designates one of the endless chains of the endless conveyor employed for carrying the bottles through the machine. Only one of the chains is shown, but it will be understood that there is one at each side of the machine and that they are of identical construction. The upper run of each chain 10 has its rollers 11 riding on a track 12 which is supported on a frame member 13 of the machine and may take the form of a bar of angle cross section. Bottle carriers 15 are provided and extend transversely of the machine and have individual compartments or pockets 16 for the bottles. Each carrier 15 is fixed at one end to a link 14 of the adjacent conveyor chain 10.

The endless conveyor is driven in any suitable manner from an electric motor 17 (see Figure 5). The details of the gearing for driving the conveyor 10 with a step-by-step motion from the motor 17 per se form no part of the present invention, and hence this is only diagrammatically illustrated in Figure 5. As there shown, the armature shaft of the motor acts through chain and sprocket gearing 18 to drive a shaft 19. On one end of the shaft 19 a one-toothed driving gear 20 is fixed and acts to drive a four-slotted gear 21 fixed to a shaft 22 which carries the driving sprockets (not shown) for the endless conveyor of chains 10. This mechanism is similar to that shown and described in the patent to Stock No. 1,729,193, although the type of external brushing mechanism contemplated in the present case differs from that shown in said patent.

A hand-operated switch, designated diagrammatically at 22, is provided in the motor circuit for the motor 17, which is diagrammatically represented as comprising power lines 23 and 24.

In one illustrative application a contactor 25 is incorporated in the circuit of the motor 17 and its movable contact 26 is biased to open position by means of a spring 26'. However, when the hand switch 22 is closed, the movable contact 26 of the contactor 25 is normally automatically closed by the electro-magnetic winding 28 of the contactor 25. The electro-magnetic coil 28 has one terminal connected by a conductor 29 to one side of the line, and has its other terminal connected by a conductor 27 to the contact 30 of a control switch, designated generally at 31.

This control switch 31 also has a contact 32 connected by a conductor 33 to the other power line 24. A bridging contact 34 is cooperable with the contacts 30 and 32, and when engaged therewith completes the circuit through the electro-magnetic winding 28 to bring contact 26 to closed position and complete the motor circuit. A spring 35, or other suitable means, biases the bridging contact 34 to closed position. The bridging contact 34 is provided with an operating button 37 of insulating material, which projects out through an opening in the housing 38 of the control switch 31 and lies in the path of movement of an adjustable abutment 39 of the switch-operating lever 40.

The switch-operating lever 40 is fulcrumed, as at 41, on a bracket 42 carried by the housing 38 of the control switch 31. Gravity tends to swing the switch-operating lever 40 away from the operating button 37 of the control switch 31 and to cause an intermediate portion of this lever to bear or wipe against an operating cam 43 provided therefor. The cam 43 is

fixed to a rotatable cam shaft 44 supported in suitable bearings 45 provided therefor on the bracket 42. A crank arm 46 is also fixed to this shaft 44 and has its outer end connected by means of a link 47 with a long lever arm 48, the link being pivotally connected to the arm 46 at one end and at its opposite end to one end of the lever arm 48. The other end of lever arm 48 is fixed to a rock shaft 49 rotatably supported in bearings provided therefor on the extension 50' of the housing 50 for the external brush mechanism to be hereinafter described. An elongated shoe 51, which is disposed lengthwise of the upper run of one of the endless conveyor chains 10, and which has upturned and rounded ends 52, rides on its run of the conveyor chain and has fixed thereto a transversely extending plate-like arm 53 which is secured to the shaft 49. The shoe 51 and its plate-like arm 53 are heavier than the lever arm 48 and parts connected to the upper end thereof and bias the lever arm 48 to engage a stop lug 54 when the shoe 51 is in normal (non-elevated) position.

The external brushing mechanism (per se, well-known in the art) is made up of rotary brushes 60 which are driven in any suitable manner, and which overlie the upper run of the endless conveyor. This external brushing mechanism also includes vertically movable washing spindles 61, which, when the conveyor is at rest, are automatically moved upwardly to engage the bottles, lift them from pockets 16, and pass them between and against the brushes 60. If any of the bottles, while being so operated upon by the external brushing mechanism, should jam the mechanism, the endless conveyor chain will be elevated from the position shown in Figure 3 to the position shown in Figure 4. This will elevate the shoe 51 and act through its arm 53, shaft 49, lever arm 48, link 47, crank arm 46, shaft 44, and cam 43, to swing the lever 40 in a clockwise direction from the position shown in Figure 3 to the position shown in Figure 4, thereby opening the switch 31 since the bridging contact 34 is shifted away from the contacts 30 and 32 thereof. This deenergizes the winding 28 of the contactor 25 and allows the spring 26' to move the contact 26 to open position, thereby stopping the motor. When the conditions causing the jamming are corrected, the device automatically resets itself.

The control switch 31, its operating lever 40, the control shoe 51, and the linkage between the control shoe and the cam 43 which operates the switch lever, may also be utilized to stop the machine when combined with an electro-magnetically or solenoid controlled clutch incorporated in the drive line or gearing provided between the motor 17 and the endless chain conveyor of the machine. For example, as shown in Figure 6, these parts may be provided as before, but the contactor 25 is omitted, and in its place the coil or winding 70 of a solenoid or the like may be substituted. As indicated, the contact 30 of the control switch 31 may be connected by a wire 71 to one terminal of the winding or coil 70, whereas the other terminal of this coil or winding is connected by conductor 72 to one side of the power line. The core or plunger 73 of the solenoid may be operatively interconnected with the operating mechanism 74 of the clutch shown diagrammatically at 75 and suitably incorporated in the drive gearing between the motor 17 and the conveyor.

The drawings illustrate the jaw clutch merely for the sake of simplicity in illustration. Any

suitable type of clutch may be employed. Likewise, any appropriate electromagnetic operating mechanism therefor may be utilized.

While I have shown and described several constructions in which the invention may be advantageously embodied, it is to be understood that the constructions shown have been selected merely for the purpose of illustration or example, and that various changes in the size, shape, and arrangement of the parts may be made without departing from the spirit of the invention or the scope of the subjoined claims.

I claim:

1. A bottle-washing machine having an endless chain conveyor for carrying the bottles through the machine in an inverted position, motor-driven means for imparting a step-by-step movement to said endless chain conveyor, external brush mechanism for the bottles including rotary brushes disposed above the conveyor and bottle-lifting spindles beneath the conveyor for engaging and lifting the bottles against the brushes, and mechanism for automatically stopping the action of the motor-driven means upon jamming of the external brushing mechanism and consequent buckling of the endless chains of the conveyor and comprising a control switch for the motor, an operating lever for said switch effective to control the opening and closing thereof, a cam for actuating said operating lever, a shoe riding on a run of the conveyor and elevated thereby when the conveyor buckles upon jamming of the external brushing mechanism, and motion transmission means operatively interconnecting said shoe and said cam.

2. A bottle-washing machine having an endless chain conveyor including a horizontal run for carrying the bottles in an inverted position, a track upon which said horizontal run travels, motor-driven means for moving said conveyor with a step-by-step motion, external brushing mechanism for the bottles including rotary brushes disposed above the conveyor, bottle-lifting spindles beneath the conveyor for engaging and bringing the bottles against the brushes, a shoe riding upon the top of the horizontal run of the conveyor and elevated thereby upon buckling of the chain consequent to jamming of the external brushing mechanism, a switch for controlling the operation of the motor, and motion transmission means between the shoe and the switch for automatically opening the switch to stop the action of said motor-driven means upon elevation of said shoe.

3. A bottle-washing machine having an endless chain conveyor for carrying the bottles through the machine in an inverted position, motor-driven means for imparting a step-by-step movement to said endless chain conveyor, external brushing mechanism for the bottles including rotary brushes above the conveyor and bottle lifting spindles beneath the conveyor for engaging and lifting the bottles against the brushes, and mechanism for automatically stopping the action of the motor-driven means upon jamming of the external brushing mechanism and consequent buckling of the chain conveyor and comprising a shoe riding on a run of the endless chain conveyor, a control switch for the motor and linkage interconnecting the shoe and the switch and acting to automatically open the switch upon buckling of the chain.

4. A bottle-washing machine having a chain conveyor for carrying the bottles through the

machine, motor-driven mechanism for actuating said conveyor, control means for said mechanism including a control switch, a shoe riding on a run of the conveyor and automatically shifted when the chain buckles upon jamming of instrumentalities of the machine, and motion transmission mechanism interconnecting said shoe and said switch and acting to open the switch and stop the action of said motor-driven means when the shoe is shifted by the buckling of the chain.

5. A bottle-washing machine having a chain conveyor for carrying the bottles through the machine, motor-driven mechanism for actuating said conveyor, control means for said mechanism including a control switch, an operating lever for said switch effective to control the opening and closing thereof, a cam for actuating said operating lever, a shoe riding on a run of the conveyor and elevated thereby when the conveyor buckles upon jamming of the machine, and linkage operatively interconnecting said shoe and said cam.

6. A bottle-washing machine comprising an endless chain conveyor for carrying the bottles through the machine, electric motor-driven means for actuating the conveyor, control means for said motor including a control switch biased to closed position, a switch-operating lever acting when swung in one direction to open said switch and stop the machine, a shoe riding on a run of the conveyor and elevated thereby when the conveyor chain buckles upon jamming of the machine, and motion transmission means actuated by the shoe and connected to said lever to swing the lever in the direction to open the switch when the shoe is elevated.

7. A bottle-washing machine comprising an endless chain conveyor for carrying the bottles through the machine, motor-driven means for actuating the conveyor, a control device to start and stop said motor-driven means, an operator for said control device, a shoe riding on a run of the conveyor and elevated thereby when the conveyor chain buckles upon jamming of the machine, and motion transmission means actuated by the shoe and connected to the operator to cause the operator to shift the control device to a position to stop said motor-driven means when the shoe is elevated.

8. A bottle-washing machine including an endless flexible conveyor for carrying the bottles through the machine, said endless flexible conveyor buckling upon jamming of the machine, a shoe riding on the conveyor and shifted thereby upon buckling of said conveyor, and means actuated by the shifting of the shoe to automatically stop the machine.

9. A bottle-washing machine comprising an endless chain conveyor for carrying the bottles through the machine, motor-driven means for imparting a step-by-step movement to said endless chain conveyor, a clutch incorporated in said means, an electro-magnetic control for said clutch, a switch for regulating the action of said electro-magnetic control, a shoe riding on a run of the conveyor and shifted thereby when the conveyor buckles on jamming of the machine, and means actuated by the shoe and effective to operate the switch to cause disengagement of the clutch and stoppage of the machine when the shoe is shifted.
